UNITED STATES PATENT OFFICE.

EDWIN R. CROOKER, OF LOS ANGELES, CALIFORNIA.

BATH-MAT.

1,190,266.

Specification of Letters Patent. Patented July 11, 1916.

Application filed November 23, 1915. Serial No. 63,100.

To all whom it may concern:

Be it known that I, EDWIN R. CROOKER, a citizen of the United States, and a resident of Los Angeles, in the county of Los Angeles and State of California, have invented a new and useful Improvement in Bath-Mats, of which the following is a specification.

This invention relates to bath mats and more particularly to impervious or non-absorbent mats for collecting and holding bath water. Such mats are frequently used in country homes, camps or other places not equipped with bath tubs or modern plumbing or water supply systems, and where the bather stands on the mat and directs the water from an overhead supply tank over his body, said water flowing down and collecting in the mat to be carried out therein and thrown away.

The object of the invention is to provide a simple and inexpensive bath mat which may be made of one piece without seams, cracks, or glued or cemented joints of any kind, so that it is durable and practically completely leakproof; and one which is light, compact and strong and is heavily reinforced at the usual weak places, both against repeated folding and unfolding and against ordinary wear and tear.

Further objects of the invention are in part obvious and in part will appear more in detail hereinafter.

The invention comprises the bath mat hereinafter described and claimed.

In the drawings, Figure 1 is a bottom plan view of a partially folded blank from which the mat is formed; Fig. 2 is a similar view of the completely folded blank; Fig. 3 is a perspective view of a complete mat; Fig. 4 is a detail perspective view, on a larger scale, looking downwardly and inwardly at one of the partially formed corners of the mat, as prepared from the blank in Fig. 2; Fig. 5 is another perspective view of the same corner; Fig. 6 is a detail cross sectional view on the line 6—6, Fig. 4, and showing the corner completed with the folded portions secured to each other; Figs. 7 and 8 are perspective views showing a modified form of mat; Figs. 9 and 10 are similar views, illustrating still another modification; and Fig. 11 is a perspective view of the bottom of the mat shown in Fig. 9.

Referring to the drawings, the mat is made of a single flat sheet 1, preferably

made of impervious or non-absorbent material, such as a rubber sheet, or a sheet of textile fabric coated on one or both sides with gum, rubber or similar material. It is 60 consequently flexible and can be rolled or folded up into a compact parcel for shipping, storage, or packing, and yet can be opened out to cover a large area for collecting the bath water. The sheet 1 is preferably 65 rectangular, and may be either square or oblong, and while hereafter I refer to "ends" and "sides" of the sheet or mat, it will of course be understood that these words are not to be considered as limiting 70 the invention in any way as regards relative dimensions of the mat.

The flat sheet 1 is first folded into a blank, the first operation, consisting in folding inwardly upon the body portion of the sheet 75 its side marginal portions 2, and then folding in the end marginal portions 3 upon the body portion and folded side portions 2. In Fig. 1 both side portions and one end portion have been folded inwardly, while in Fig. 2 both side and both end portions are folded to produce the complete blank. The folded side and end portions 2 and 3 of the blank are on the outside of the completed mat, so that the inner surface of the mat is 80 formed by the unbroken surface of the body portion of the sheet, and has no cracks, crevices or openings of any kind, and therefore prevents wholly the escape of water 85 from the mat. The peripheral portions of the blank are also reinforced, stiffened and strengthened by folding the edge portions onto the body, which produces four thicknesses or plies of material at the corners 4, where the sides and ends overlap each other, 90 and two plies of material between said corners along the sides and ends, although by infolding the edge portions a greater number of times than as shown the number of plies of material at the corners and edges of 95 the blank may be readily increased.

The folded blank shown in Fig. 2 is turned over so that the infolded edge portions are on the bottom, and is then folded up into shallow tray form, so as to produce 105 a rim or wall 6 around the periphery of the mat to hold the water therein. Said rim or wall is of uniform depth or height around the entire mat, and preferably its height is less than the width of the infolded portions 110 2 and 3. In the drawings, the rim or wall is approximately half the width of the in-

folded portions, so that in the completed mat said infolded portions extend down along the outside of the rim or wall and inwardly beneath the mat toward its center, as indicated at 7, consequently reinforcing all portions of the rim or wall by a two-ply base or body underneath the same.

The corner joint of the completed mat may be of any suitable form, and several types thereof are shown in the drawings. For example, in Fig. 4 the corner joint is formed by folding inwardly the square corner portion 8 of the blank, which is folded upon itself into two plies along a diagonal line of fold 9. This corner fold is of a well known form and is superposed upon an adjacent portion of the rim or wall 6 at either the side or end of the tray, and is preferably suitably secured thereto so as to prevent the mat from collapsing or unfolding. One suitable securing means consists of an ordinary staple or paper fastener 10 passed through openings 10^a in the folded corner 8 and the adjacent portion of the rim or wall 6. The folded corner portion 8 may also be folded outwardly, as in Fig. 7, and lapped on the outside instead of on the inside of the rim or wall, as shown in Fig. 8, and is secured thereto by a staple or paper fastener 10 in the same manner as illustrated in Fig. 4.

In both of the arrangements just described a single securing device, such as the staple 10, is sufficient at each corner of the mat, but to further lock the corners when necessary the superposed plies of the infolded end and side portions of the mat may be secured to each other by a similar staple or fastener 11, as shown in Fig. 6. Said fastener will be inserted from beneath and will not extend through the body portion of the sheet, which is therefore left unbroken or imperforate, so that no water can escape therethrough. By taking out the paper fasteners or staples 9 and 11 the mat can be readily rolled up for packing.

Figs. 9, 10 and 11 show another arrangement in which the corner joints are made by lapping the folded corner portions on the outside of the rim or wall, as in Fig. 7. In this form, however, the square two-ply portion 12 of the infolded material at each end of the infolded ends 3, is folded underneath the body portion of the mat in the form of a triangular four-ply fold 13. This reduces the number of superposed plies on the end portion of the rim or wall 6, and diverts some of the material to a position underneath the body of the mat, so that at the triangular fold 13 there are eight plies or material through the bottom. This form of corner is securely fastened by staples or paper fasteners 14 passed through the triangular fold 13 and the superposed portions of the end and side infolds, but not through the

body portion of the sheet, in the same manner as in Fig. 6, and also a staple or paper fastener 15 passed through the plies of the rim or wall. By carrying a portion of the folded corner beneath the mat it is reinforced at its corners against wear from the floor or other support upon which the mat is placed, while the mat also has a neater appearance at its corners.

The securing staples described may of course be dispensed with and the several superposed plies of material secured to each other in any other suitable manner, as by an adhesive cement. Said cement, however, does not form a joint to prevent leakage of the liquid but merely acts as a mechanical binding means for holding the parts together.

This mat is of very simple construction as it embodies merely a single ply of material folded upon itself into a tray form and secured at its corners by staples, paper fasteners, or other simple form of securing device. Consequently it can be manufactured very cheaply and is also more durable than prior mats of this form, due to the absence of stitched, glued or cemented joints which open up in use and through which the water leaks. The material of course is flexible so that the completed mat can be folded or rolled into a compact parcel and consequently can be conveniently stored away when not in use. The mat is also self-supporting and requires no braces or other frame parts for holding up its rim or wall. It is self-contained and can be transported from place to place and used with any water source, so that it is convenient for traveling men and in any place where a bath tub is not accessible.

What I claim is:

1. A bath mat, comprising a flexible sheet having its side and end portions folded in upon the body, the infolded periphery being folded to form a rim or wall.
2. A bath mat, comprising a flexible sheet having its side and end portions folded in upon the body, the infolded periphery being folded to form a rim or wall, said infolded portions lying on the outside of the mat.
3. A bath mat, comprising a flexible sheet having its side and end portions folded in upon the body, the infolded periphery being folded to form a rim or wall, said infolded portions lying on the outside of the mat and extending beneath the same.
4. A bath mat, comprising a flexible sheet having its side and end portions folded in upon the body, the infolded periphery being folded to form a rim or wall, and means for securing the infolded portions of the sheet to each other.
5. A bath mat, comprising a flexible sheet having its side and end portions folded in upon the body, the infolded periphery being

folded to form a rim or wall, said infolded portions lying on the outside of the mat, and means for securing the infolded portions of the sheet to each other.

5 6. A bath mat, comprising a flexible sheet having its side and end portions folded in upon the body, the infolded periphery being folded to form a rim or wall, said infolded portions lying on the outside of the mat and 10 extending beneath the same, and means for securing the infolded portions of the sheet to each other.

15 7. A bath mat, comprising a flexible sheet having its side and end portions folded in upon the body, the infolded periphery being folded to form a rim or wall, and fastening means passing through the superposed infolded portions of the mat.

20 8. A bath mat, comprising a flexible sheet having its side and end portions folded in upon the body, the infolded periphery being folded to form a rim or wall, said infolded portions lying on the outside of the mat and 25 extending beneath the same, and fastening means passing through the superposed infolded portions beneath the corners of the mat.

30 9. A bath mat, comprising a flexible sheet having its side and end portions folded in upon the body, the infolded periphery being folded to form a rim or wall, the corner parts of the infolded portions being superposed upon adjacent portions of said rim or 35 wall.

10. A bath mat, comprising a flexible sheet

having its side and end portions folded in upon the body, the infolded periphery being folded to form a rim or wall, the corner parts of the infolded portions being superposed upon adjacent portions of said rim or 40 wall, and means for securing the same thereto.

11. A bath mat, comprising a flexible sheet having its side and end portions folded in upon the body, the infolded periphery being folded to form a rim or wall, the corner parts of the infolded portions being superposed upon adjacent portions of said rim or 45 wall and the exposed end portions of the infolded periphery being folded beneath the corner.

12. A bath mat, comprising a flexible sheet having its side and end portions folded in upon the body, the infolded periphery being folded to form a rim or wall, the corner parts of the infolded portions being superposed upon adjacent portions of said rim or 50 wall and the exposed end portions of the infolded periphery being folded beneath the corner, and securing means passing through the superposed infolded portions beneath the corners of the mat and also through the last named folded exposed end portion of the infolded periphery.

65 In testimony whereof, I have hereunto set my hand.
